WAVE GENERATOR

Madison Cawein, Fort Wayne, Ind., assignor, by
mesne assignments, to Farnsworth Research
Corporation, a corporation of Indiana

Application January 11, 1943, Serial No. 471,977

14 Claims. (Cl. 250—36)

1

This invention relates to generators of periodic waves of complex form and particularly to generators of the oscillator type for producing periodic currents having a complex wave form.

According to conventional practice in the use of tubes employing beams of electrons, such as a dissector tube used at the transmitter in a television system, or a cathode ray tube used at the receiver in such a system, it is customary to deflect the electron beam for scanning purposes by means of either an electrostatic or an electromagnetic field. These fields are required to have saw-toothed wave forms. Where it is desired to produce an electromagnetic field of saw-tooth wave form it is necessary to supply, to the deflecting coils of the tube, periodic current of such wave form that the field will have the desired saw-toothed wave form. Numerous current generators of the oscillator type have been proposed for such a purpose. Typical of such oscillators is that disclosed in United States Patent No. 2,059,683, granted to Philo T. Farnsworth on November 3, 1936. A limitation of this type of generator is that, for certain uses, it is incapable of supplying currents of sufficient magnitude.

An object of the present invention, therefore, is to provide an improved oscillator for generating periodic current waves of complex form, such as, for example, waves of saw-tooth or related forms.

Another object of the invention is to provide an oscillator for generating saw-tooth current waves of greater magnitude and of more linear wave form than heretofore obtainable.

Still another object of the invention is to provide a saw-tooth oscillator employing fewer circuit components and a simpler circuit than used heretofore.

A further object of the invention is to provide a saw-tooth oscillator having a higher operating efficiency than heretofore obtainable.

A still further object of the invention is to provide a saw-tooth oscillator having sufficient circuit flexibility to be adaptable, by simple switching means, for operation at widely different frequencies.

Another object of the invention is to provide a novel electronic means for controlling the rates of increase and decrease of current in a circuit which includes inductance and resistance.

In an effort to modify an oscillator of the type disclosed in the Farnsworth patent referred to for the production of larger deflection currents of better wave forms, a beam power type tube was substituted for the tetrode used by Farnsworth. The other circuit components were retained without substantial alteration except in the constants thereof. However, the substitution of the beam power tube for the tetrode produced results which were considerably beyond the scope of reasonable

2

expectancy and constituted material improvements over the results obtainable with the Farnsworth oscillator. The generated current was found to have a smaller semi-exponential component than heretofore, thereby constituting an improvement in the wave form. There was also found to be a substantial increase in the magnitude of the generated current. Incidental to, or perhaps instrumental in, the production of these improved results, it was discovered that the control of the frequency and amplitude characteristics of the generated wave was effected in a manner differing from the control of the corresponding characteristics in the Farnsworth oscillator. Thus, cut-off is relatively absolute and results in a relatively steeper wave front than in other existing circuits.

In accordance with the present invention there is provided an oscillator for generating large periodic currents of complex wave form which includes an electronic device, such as a beam power tube, adapted to form a concentrated electron beam. There is connected in the anode or output circuit of the tube an inductance. Another inductance closely coupled to the anode inductance is connected in the control grid or input circuit of the tube. The inductances are poled so that an increase in anode current will apply a positive potential of such magnitude to the grid that the impedance of the tube is reduced to a relatively low value. A positive potential of predetermined magnitude is connected to the screen grid of the tube through an impedance. The periodic current wave of complex form is derived from the inductance connected to the control grid of the tube. If desired, high voltage potentials may be derived from the anode inductance which may be rectified to produce a high voltage direct current.

There are also provided facilities for changing the frequency of the generated current wave without effecting any appreciable change in the amplitude thereof. Additional facilities are provided for making refinements in the wave form of the generated wave to render it more suitable for use with deflecting coils for the production of an electromagnetic field for scanning purposes.

For a better understanding of the invention, together with other and further objects thereof, reference is had to the following description taken in connection with the accompanying drawings and its scope will be pointed out in the appended claims.

In the accompanying drawings:

55 Fig. 1 is a circuit diagram of an oscillator for generating periodic current waves of a complex form and embodying the present invention;

Fig. 2 illustrates a series of curves characteristic of voltages appearing in some of the circuits 60 of Fig. 1;

Figs. 3 and 4 show modified circuit connections between the output terminals of the oscillator and the deflecting coils of a tube of the cathode ray type;

Fig. 5 is a circuit diagram of an oscillator similar to that illustrated in Fig. 1 in which are incorporated facilities for changing the nominal frequency of the generated wave without changing the amplitude thereof; and

Fig. 6 is a further modification of the oscillator of Fig. 1 which incorporates facilities for producing periodic waves of improved wave form.

Referring now more particularly to Fig. 1 of the drawings, the oscillator embodying the present invention includes a beam power tube 10, having a cathode 11, a control grid 12, a screen grid 13, beam-forming elements 14 and an anode 15. The cathode 11 is connected internally of the tube to the beam-forming plates.

Externally, the cathode 11 is connected through an adjustable resistance 16 and the complete resistance portion of a potentiometer 17 to the negative terminal of a source of direct current, such as a battery 18. The negative terminal of the battery is also connected to ground, as shown. The anode 15 of the tube is connected through an inductance 19, which forms the primary winding of an iron-core transformer 20, and an adjustable resistance 21 to the positive terminal of the battery 18.

The control grid 12 of the tube is connected through an inductance 22 forming a secondary winding of the transformer, to an intermediate tap on the resistance element of the potentiometer 17. The screen grid 13 of the tube is connected through a fixed resistance 23 and the adjustable resistance 21 to the positive terminal of the battery 18.

The output circuit for the current wave generator comprises the connection of terminal 24 to the control grid 12 of the tube and the connection of the terminal 25 to the adjustable slider element 26 of the potentiometer 17. Connected to the output terminals 24 and 25 is a series arrangement of the deflection coils 27 of a cathode ray tube. There is provided, in shunt with the deflection coils, a series shaping network of an inductance 28 and a resistance 29.

The screen grid 13 of the tube 10 may be connected to a terminal 30. The junction point of the fixed and adjustable resistances 23 and 21 respectively, may be coupled by means of a blocking condenser 31 to a terminal 32 which is connected to ground. There may be applied to terminals 30 and 32 synchronizing pulses for the purpose of correlating the operation of the oscillator with the signals applied to the control element of the cathode ray tube.

Where it is desired to utilize the high voltage appearing periodically at the anode 15 of the tube 10, there is provided a rectifier tube 33 having its anode connected to the anode 15 of the tube 10 and its cathode connected to an auxiliary winding 34 on the transformer 20 which is utilized for heating purposes. The cathode of the rectifier tube is connected to a positive direct current output terminal 35. The negative direct current output terminal 36 is connected to ground and is coupled to terminal 35 by a filter condenser 37.

Considering now the operation of the apparatus illustrated in Fig. 1, reference will be made to certain observable characteristics of the oscillator before considering a suggested theory of operation which will be offered subsequently. Accordingly, the voltages which are known to exist at certain

times in the various circuits associated with the elements of the beam-power tube will be referred to. Such voltages are illustrated by the curves of Fig. 2.

The connection of the circuit of the control grid 12 to the resistance element of the potentiometer 17, introduces into this circuit a negative bias potential produced by the flow of cathode current through the resistance. However, the poling of the transformer windings 19 and 22 is regenerative so that, with an increase in the current through the primary winding 19, a positive potential derived from the secondary winding 22 is also introduced into the control grid circuit. During periods of current increase in the primary winding the positive potential is of sufficient magnitude to predominate over the negative potential and to thereby render the control grid sufficiently positive to reduce the impedance of the tube 10 to a relatively low value. During periods of current decrease in the primary winding a negative potential, derived from the secondary winding 22, is introduced into the control grid circuit which, in itself, is sufficient to increase the impedance of the tube 10 to infinity. There is also provided a positive bias for the screen grid 13 which is of a predetermined minimum magnitude depending upon the values of the fixed resistance 23, the adjustable resistance 21 and the voltage of the battery 18.

A cycle of operation will be assumed to start with the closing of the cathode-to-anode path within the tube 10. Current starts to flow in the series circuit comprising the battery 18, the adjustable resistance 21, the transformer primary winding 19, the space current path of the tube 10, the adjustable resistance 16 and the resistance element of the potentiometer 17.

The impedance of the anode-to-cathode path within the tube constitutes the major part of the resistance portion of the circuit. Consequently, the impedance of the variable resistance 16 and the potentiometer 17 may be neglected for the present purpose. By reason of the inclusion of the inductive primary winding 19 in this circuit, the current increase with respect to time is gradual. During the time that the current is increasing in this circuit, the potential of the cathode 11 of the beam power tube 10 is becoming more positive, as indicated by the curve 38 of Fig. 2. At the same time, the potential applied to the screen grid 13 of the tube is becoming increasingly positive, as indicated by the curve 39. Concurrently with these voltage changes, the voltage of the anode 15 of the tube remains at a substantially constant negative value, as indicated by the curve 40. Also the potential applied to the control grid 12 similarly remains at a substantially constant value which is positive, as indicated by the curve 41. These conditions exist for a period of time which, it has been found, is determined primarily by the ratio of the inductance external of the tube 10 to the internal resistance of the tube included in the series anode-to-cathode circuit of the tube. If no synchronizing signals are applied to the terminals 30 and 32 and the oscillator is permitted to function under the sole influence of the self-excitation provided, the current increase between the cathode and anode of the tube 10 suddenly stops when a critical inter-electrode potential relation is reached and a sharp decrease in this current ensues. A complete interruption of the current flow is effected in a much shorter time

than in prior art devices, such as the Farnsworth oscillator.

At this point the anode voltage rises momentarily to a sharp positive peak indicated by the curve 42. The amplitude of this peak is considerably in excess of the voltage of the battery 18. Also, at this time, the potential of the control grid 12 is momentarily reduced to a high negative value which is in excess of the negative biasing effected by the self-biasing resistance element of the potentiometer 17. This momentary negative potential is represented by the curve 43. Coincidentally with the appearance of these potential peaks, the positive potential of the screen grid 13 rises sharply to a value which is substantially equal to that of the battery 18. This potential change is indicated by the curve 44. Also, the potential of the cathode 11 is suddenly reduced to zero, as indicated by the curve 45. The potentials represented by the curves 42, 43, 44 and 45 exist only for the short period of time that the cathode-to-anode current is interrupted. The potentials of the tube elements then revert to their initial polarities and values, resulting in the reclosing of the cathode-to-anode path within the tube 10 and the repetition of the described cycle.

The output circuit connected to terminals 24 and 25 is derived by connections made respectively to the control grid 12 and to the slider 26 of the potentiometer 17. Consequently, the potential appearing at the terminals 24 and 25 varies in accordance with the variation of the control grid potential with respect to the potential of the cathode. From the curves of Fig. 2, it is seen that, during the major portion of the cycle, the control grid potential has a substantially uniform value while the cathode potential has an increasing value. It is readily seen, therefore, that the potential of the output circuit has a complex wave form which is substantially a saw-tooth form as indicated by the curve 46. The current flowing through the circuit connected to terminals 24 and 25, therefore, has a wave form suitable for the creation of an electromagnetic field by the deflection coils 27 which has a saw-tooth form. For the purpose of absorbing any exponential component which may appear in the generated current wave, there is provided a series network of the inductance 28 and the resistance 29 connected in shunt with the deflection coils 27.

The frequency of the current wave produced by the oscillator embodying the present invention, is determined primarily by the ratio of the external inductance represented by the primary winding 19 of the transformer 20, to the internal resistance of the tube 10. These frequency-determining facilities are substantially different from the facilities provided for a similar purpose in the oscillator disclosed in the Farnsworth patent referred to. In the Farnsworth oscillator, the frequency control is effected by adjusting the value of the grid leak resistance connected from the control grid to ground. The corresponding element in the present oscillator is the right-hand portion 47 of the resistance element of the potentiometer 17. In the oscillator, in accordance with the present invention, variation in the frequency of the generated current wave may be effected by varying either the inductance of the winding 19 or the resistance of the tube 10. It is most conveniently effected by varying the value of the adjustable resistance 16 which thereby changes the bias of the control grid 12. Thus, the internal resistance of the tube is changed,

thereby altering the inductance-to-resistance ratio of the cathode-to-anode series circuit. It has been found that the actual impedance of the primary and secondary transformer windings 19 and 21 respectively, are not at all critical for the successful operation of the oscillator.

The adjustment of the variable resistance 21 effects a control of the amplitude of the high peaks of anode voltages produced by the operation of the present oscillator, and also controls the speed of the generated current wave. The latter control determines the time required for the generated current wave to change from its maximum to its minimum value. The adjustable resistance 21 also controls the susceptibility of the oscillator to synchronizing pulses. It has been found that for every design of an oscillator of this type there are certain optimum values of impedance and positive potential connected to the screen grid 13.

If synchronizing potential pulses of negative polarity and predetermined magnitude are applied to terminals 30 and 32 at a slightly higher frequency than the free oscillation frequency of the current wave generator, the cathode-to-anode current interruptions are induced thereby slightly before the occurrence of the described self-induced interruptions. Thus, one cycle is ended and a new one started in synchronism with the synchronizing pulses.

The apparatus connected in the manner described and illustrated in Fig. 1, has been found to give satisfactory results for the purpose described when using circuit elements and constants in accordance with the following table:

Tube 10—Type 6AL6G	
Variable resistance 16—100 ohms; 2 watts	
Potentiometer resistance 17—60 ohms; 2 watts	
Battery 18—300-400 volts	
Primary winding 19—600 millihenries; 700 turns	
Secondary winding 22—10 millihenries; 85 turns	
Fixed resistance 23—5000 ohms; 10 watts	
Variable resistance 21—6000 ohms; 10 watts	
Deflecting coils 27—2.15 millihenries	
Inductance 28—3.5 millihenries	
Resistance 29—1000 ohms; 10 watts	

It is believed that a fuller appreciation of the marked distinction of the oscillator embodying the present invention over prior art oscillators may be derived from a consideration of the following suggested theory of operation. It seems evident from a study of the curves of Fig. 2, that the interruption of the cathode current, once it is started, is accelerated at such a high rate that the current cut-off is relatively absolute. The acceleration is apparently caused by the negative impulsive potential of the control grid 12, as indicated by the peak 43. This potential is developed by the regenerative coupling of the transformer windings 19 and 22 in response to the slight lessening of the rate of increase of the cathode current. Up to a certain point, this rate of increase is constant. As the cathode current starts to increase, it is seen from the curve 39 that the potential of the screen grid 13 is at its lowest value. This is probably due to the deflection of a large number of electrons toward the screen grid at this time. As the cathode current increases, the potential of the cathode also increases, as evidenced by the curve 33. The potentials of the beam-forming electrodes 14 also increase similarly since they are connected internally of the tube to the cathode 11. It appears likely that as the potentials of the beam-

forming electrodes increase, the number of electrons which are deflected toward the screen grid decreases at the same rate until the potential of the screen grid reaches a value at which a part of the electron beam strikes the beam-forming electrodes. This action initiates interruption of the cathode current which then, because of the regenerative action of the device, completely ceases substantially instantaneously.

Control of the deflection amplitude of the electron beam under the influence of the deflecting coils 27 may be effected in a number of ways. In Fig. 3 there is provided in series with the deflecting coils an adjustable inductance device 48 by means of which a variation in the deflection amplitude may be secured.

In Fig. 4 the deflecting coils 27 are shunted by a series network similar to that shown in Fig. 1. In this case, however, the reactive element is an adjustable inductance device 49 and the non-reactive element is an adjustable resistance 50. A variation of the value of the adjustable inductance 49 effects the desired change in the deflection amplitude. However, since any change in the value of this element alters the effectiveness of the shunting circuit as a means for refining the wave form of the deflection currents, an adjustment of the resistance 50 is necessary to maintain the wave form correcting effectiveness of the circuit at an optimum value.

In Fig. 5 the arrangement of the circuit elements comprising the oscillator is, with the exception of certain refinements which will be described presently, substantially identical with the arrangement of Fig. 1. For the purpose of effecting still another control of the deflection amplitude, there is provided in the connection between the anode of the tube 10 and the anode of the rectifier tube 33 an adjustable resistance 51. By means of this device, the magnitude of the direct current appearing at the terminals 35 and 36 may be varied. In the case where this direct current is used as the source of potential for the second anode of a cathode ray tube, variations in the value of the direct current changes the stiffness of the electron beam in the cathode ray tube. In consequence of such a change a corresponding variation in the magnitude of the deflection of the beam is effected.

Fig. 5 also discloses facilities for changing the nominal frequency of the current wave generated by an oscillator of this type without changing the amplitude of the current. Such an arrangement provides a convenient device for adapting a television receiver for use in receiving signals transmitted according to a plurality of different standards.

The frequency of the generated current wave produced by an oscillator in accordance with the instant invention is determined by the ratio of the external anode inductance to the internal anode-to-cathode resistance of the beam power tube. As previously described, the most convenient means for changing this ratio is by a variation of the grid bias effected by the adjustment of one of the external resistance elements. Obviously, such a change will alter the magnitude of the current flowing in the circuit. This current traverses the primary winding 19 of the transformer 20. The value of the deflection current is a function of the product of the current flowing in the primary transformer winding 19 and the ratio of the primary winding to the secondary winding. Therefore, in view of this relation, if it is desired to maintain the value

of the deflection current constant when a frequency change is effected by the means described, it is necessary to effect a compensatory change in the transformer ratio. Such a change is effected by the facilities herein provided by decreasing the number of turns on the secondary winding whenever the current through the primary winding is decreased as a result of an increase in the resistance of a primary circuit. A compensation of this character is necessary for the additional reason that the different reactance of the deflecting coils 27 at the new frequency is reflected in the anode circuit of the tube 10. The reflection, of course, is by reason of the transformer coupling between the anode and grid circuits, the latter of which is connected to the deflecting coils.

There is shown in this figure an additional relatively low fixed resistance 52 connected in the external cathode-to-anode circuit. The terminals of this resistance are connected to a switch 53. The secondary winding 54 of the transformer 20 is provided with an intermediate tap 55 which is connected, together with the terminal 56, to another switch 57. The switches 53 and 57 may be ganged in the manner shown for simultaneous operation.

With the switches 53 and 57 in the positions shown, the resistance 52 is short-circuited and the entire secondary winding 54 is connected in the control grid circuit. The oscillator functions to generate a current wave of a frequency determined by the ratio of the inductance of the primary winding 19 to the resistance of the anode-to-cathode circuit of the tube 10. When it is desired to change the frequency of the generated current wave by a predetermined amount, the switches 53 and 57 are moved to their left hand positions. The short circuit is removed from the resistance 52 and the number of turns on the secondary winding 54, which are included between the intermediate tap 55 and the terminal 56, are disconnected from the control grid circuit. As a result of the removal of the short circuit from resistance 52 there is a decrease in the current flowing through the primary winding 19. Coincidentally, however, the ratio of primary-to-secondary turns on the transformer 20 is increased in an amount sufficient to compensate for the decrease in the primary current and for the changed reactance of the deflecting coils 27. By properly choosing the value of the resistance 52 and the number of secondary turns which are switched into and out of operation, it is obvious that the value of the deflection current can be maintained substantially constant. It will also be obvious that the oscillator may be arranged to operate at several predetermined frequencies without substantially changing the value of the deflection current by providing additional resistances similar to resistance 52 and additional secondary taps similar to the intermediate tap 55, together with additional switch contacts connected to the added facilities, in a manner similar to that shown.

In Fig. 6 there is shown an alternative means for producing a current wave of the desired form without the use of a shunting network around the deflecting coils as illustrated in Figs. 1, 3, 4 and 5. It is well known that such shunting networks function by absorbing the semi-exponential component of the generated current wave. Obviously, any device functioning in this manner absorbs power which, in most cases, may be used more advantageously for deflection pur-

poses. In the arrangement of Fig. 6 such a shunting network is not required. The transformer 20 is provided, in addition to the usual secondary winding 58, with an auxiliary winding 59. In series with the auxiliary winding is a condenser 60 and the network so formed is connected to the terminals of a resistance 61 which is inserted between the secondary winding 58 and the control grid 12 of the beam power tube 10. Such an arrangement provides an effective compensation for the non-linearity of the tube characteristic and, hence, tends to linearize the generated current wave.

The use of an oscillator in accordance with the present invention provides several advantages over the use of any prior art device of this type. The chief advantage is in obtaining a current wave suitable for deflection purposes which is of considerably greater magnitude than it has been possible to obtain heretofore. Another advantage is that the form of the generated current wave is inherently more linear than heretofore obtainable. Another advantage is the increased speed of the current wave resulting in a faster return time.

While there has been described what is at present considered the preferred embodiment of the invention, it will be obvious to those skilled in the art that various changes and modifications may be made therein without departing from the invention, and it is, therefore, aimed in the appended claims to cover all such changes and modifications as fall within the true spirit and scope of the invention.

What I claim is:

1. An oscillator for generating a saw-tooth wave comprising, an electronic device having input and output circuits and internal resistance, an external circuit coupled to said output circuit including an inductance, and an external circuit coupled to said input circuit including a second inductance regeneratively coupled to said first inductance, said electronic device being a tube of the beam power type whereby the frequency of the generated wave is determined by the ratio of said output circuit inductance to said internal resistance, and a variable external resistance connected in common to said input and output circuits to vary said internal resistance whereby to change the frequency of the generated wave.

2. An oscillator for generating a saw-tooth wave comprising, an electronic device adapted to form a concentrated electron beam and having a cathode, an anode and two grid electrodes, means for maintaining one of said grid electrodes at a predetermined positive potential, an input circuit for said device including the other of said grid electrodes and a variable resistance connected to said cathode, an output circuit for said device including said anode, said cathode and the series connection of an inductance and said variable resistance, and means including said inductance to regeneratively couple said input and output circuits, said resistance serving to control the internal resistance of said electronic device and thereby the frequency of said generated wave.

3. An oscillator for generating a saw-tooth current wave comprising, a beam power tube having a cathode, an anode, two grid electrodes and internal resistance, a first external circuit connecting said cathode and said anode including an inductance and a resistance, the ratio of said inductance to said internal resistance being the frequency-determining factor of said generated

wave, a second external circuit connecting said cathode with one of said grid electrodes including the resistance of said first external circuit and an inductance regeneratively coupled to the inductance of said first circuit, and means to maintain the other of said grid electrodes at a positive potential with respect to said cathode for determining the amplitude of said generated wave.

4. An oscillator for generating a current wave of complex form suitable for creating a magnetic field having a saw-tooth form comprising, a beam power tube having a cathode, an anode, a control grid, a screen grid and a controllable internal resistance, an external resistance connected at one end to said cathode, an anode inductance connected between said anode and the other end of said external resistance, the ratio of said inductance to said internal resistance being the principal factor in determining the frequency of said current wave, a control grid inductance connected between said control grid and said other end of said external resistance and regeneratively coupled to said anode inductance, said external resistance providing a control of said internal resistance, an output circuit for said current wave derived from said control grid inductance, and a source of direct current potential connected between said screen grid and said cathode for determining the amplitude of said current wave.
5. An oscillator for generating a saw-tooth wave comprising, a beam power tube having a cathode, an anode, a control grid, a screen grid and internal resistance, an external resistance connected to said cathode, a transformer having primary and secondary windings, a source of direct current energy, a frequency-determining circuit connecting said cathode and said anode and including a series arrangement of said internal resistance, said source of energy and said primary transformer winding, a regenerative circuit connecting said cathode and said control grid and including a series arrangement of said external resistance and said secondary transformer winding, an output circuit for said saw-tooth wave derived from said secondary transformer winding, and a circuit for determining the amplitude of said saw-tooth wave including a positive potential connected to said screen grid.
6. An oscillator for generating a saw-tooth wave comprising, an electronic device having input and output circuits and internal resistance, an external circuit coupled to said output circuit including an inductance and a resistance, an external circuit coupled to said input circuit including a second inductance regeneratively coupled to said first inductance, the frequency of the generated wave being determined by the ratio of said output circuit inductance to said internal resistance, said external resistance being variable to change said internal resistance and, thereby, the frequency of the generated wave, and means for concurrently varying said input circuit inductance to maintain a constant amplitude of the generated wave irrespective of the frequency thereof.
7. In a circuit including an inductance and a resistance, the combination for controlling the rates of increase and decrease of current in said circuit including, an electronic device having a cathode, an anode and a control grid, the cathode-to-anode internal circuit constituting said resistance, the cathode-to-anode external circuit including said inductance and a self-biasing impedance device connected to said cathode, said cathode being biased by said impedance device in

accordance with the magnitude of said current and the grid serving to control said resistance, and means for regeneratively coupling said grid to said external circuit whereby the rates of current increase and decrease cause abrupt changes of said resistance and whereby said resistance changes in turn effect changes in said rates of current increase and decrease.

8. An oscillator for generating a saw-tooth wave comprising, an electronic device having input and output circuits and internal resistance, a first inductance element coupled to said input circuit, and impedance device conductively coupled in common to said input and output circuits, and a frequency-determining circuit including the internal resistance of said electronic device and a second inductance element coupled to said output circuit and regeneratively coupled to said first inductance element.

9. An oscillator for generating a saw-tooth current wave comprising, a beam power tube having a cathode, an anode and a grid by which to control the internal resistance of said tube, an anode inductance device and a resistor connected in series between said anode and said cathode, the ratio of said anode inductance to said internal resistance being the principal factor in determining the frequency of said current wave, and a grid inductance device connected between said control grid and said resistor and regeneratively coupled to said anode inductance device.

10. An oscillator for generating a saw-tooth current wave comprising, a beam power tube having a cathode, an anode and a grid by which to control the internal resistance of said tube, an anode inductance device and a resistor connected in series between said anode and said cathode, the ratio of said anode inductance to said internal resistance being the principal factor in determining the frequency of said current wave, a grid inductance device connected between said control grid and said resistor and regeneratively coupled to said anode inductance device, and an output circuit for said current wave derived from said grid inductance device.

11. An oscillator for generating a saw-tooth current wave comprising, a beam power tube having a cathode, an anode, a screen grid and a control grid by which to vary the internal resistance of said tube, a series external anode-to-cathode circuit including an anode inductance device connected to said anode and a resistor connected to said cathode, the ratio of said anode inductance to said internal resistance being the principal factor in determining the frequency of said current wave, a control grid inductance device connected between said control grid and said resistor and regeneratively coupled to said anode inductance device, and a source of synchronizing signals coupled in negative polarity to said screen grid.

12. An oscillator for generating a saw-tooth wave comprising an electron discharge device having an anode, a cathode, a control grid, a screen grid and an electrode connected to said cathode for suppressing the flow of secondary electron current from said anode to said screen grid, an anode inductance device and an impedance device connected in series between said anode and said cathode, the ratio of said anode inductance device to the internal resistance of said electron discharge device being the principal factor in determining the frequency of said saw-tooth wave, a grid inductance device con-

nected between said control grid and said impedance device and regeneratively coupled to said anode inductance device, means including a resistor for impressing upon said screen grid a positive voltage with respect to said cathode, and means for impressing synchronizing signals of negative polarity upon said screen grid.

13. An oscillator for generating a saw-tooth wave comprising, an electron discharge device having an anode, a cathode, a control electrode to vary the internal resistance of said device between said anode and said cathode, a screening electrode to minimize the interelectrode capacity between said anode and said control electrode and a suppressor electrode connected to said cathode for minimizing the flow of secondary electron current from said anode to said screening electrode, a first inductance device coupled to said anode and an impedance device connected in series therewith and coupled to said cathode, the ratio of said first inductance device to the internal resistance of said electron discharge device being the principal factor in determining the frequency of said saw-tooth wave, and a second inductance device coupled between said control electrode and said impedance device and regeneratively coupled to said first inductance device.
14. An oscillator adapted to drive a substantially saw-tooth current wave through an electromagnetic ray deflecting coil of a cathode ray tube comprising, an electron discharge device having an anode, a cathode, a control electrode to vary the internal resistance of said device between said anode and said cathode, a screening electrode to minimize the interelectrode capacity between said anode and said control electrode and a suppressor electrode connected to said cathode for minimizing the flow of secondary electron current from said anode to said screening electrode, a first inductance device coupled to said anode and an impedance device connected in series therewith and coupled to said cathode, the ratio of said first inductance device to the internal resistance of said electron discharge device being the principal factor in determining the frequency of said saw-tooth wave, a second inductance device coupled between said control electrode and said impedance device and regeneratively coupled to said first inductance device, and an output circuit conductively coupled to said second inductance device.

MADISON CAWEIN.
